UNITED STATES PATENT OFFICE

149,118

DESIGN FOR A PUZZLE GAME BOARD

Louis D. Gallegos and Harold J. Byrnes,
Los Angeles, Calif.

Application November 5, 1946, Serial No. 134,532

Term of patent 7 years

(Cl. D34—5)

To all whom it may concern:

Be it known that we, Louis D. Gallegos and Harold J. Byrnes, citizens of the United States, residing at Los Angeles, in the county of Los Angeles and State of California, have invented a new, original, and ornamental Design for a Puzzle Game Board, of which the following is a specification, reference being had to the accompanying drawing, forming a part thereof.

Figure 1 is a face view of a puzzle game board, showing our new design.

Figure 2 is a sectional view of the same taken along the line 2—2 of Figure 1.

We claim:

The ornamental design for a puzzle game board, as shown.

LOUIS D. GALLEGOS.
HAROLD J. BYRNES.
